(57) **CLAIM**

We claim the ornamental design for a hydroponic growing container, as shown and described.

DESCRIPTION

FIG. 1 is a front perspective view of a first embodiment of the hydroponic growing container showing our new design;
FIG. 2 is a front elevation view of FIG. 1;
FIG. 3 is a first side elevation view of FIG. 1;
FIG. 4 is a second side elevation view of FIG. 1;
FIG. 5 is a back elevation view of FIG. 1;
FIG. 6 is a top plan view of FIG. 1;
FIG. 7 is a bottom plan view of FIG. 1;
FIG. 8 is another perspective view of FIG. 1;
FIG. 9 is perspective view of a second embodiment of the hydroponic growing container of FIG. 1;
FIG. 10 is a front elevation view of FIG. 9;
FIG. 11 is a first side elevation view of FIG. 9;
FIG. 12 is a second side elevation view of FIG. 9;
FIG. 13 is a back elevation view of FIG. 9;
FIG. 14 is a top plan view of FIG. 9;
FIG. 15 is a bottom plan view of FIG. 9; and,
FIG. 16 is another perspective view of FIG. 9.

The broken lines are included for the purpose of illustrating portions of the hydroponic growing container that form no part of the claimed design.
